Des. 233,536
Patented Nov. 5, 1974

233,536

POLO GOAL

Don C. Herold, 10023 Hocker Drive,
Merriam, Kans. 64106

Filed Aug. 31, 1972, Ser. No. 285,472

Term of patent 14 years

Int. Cl. D21—02

U.S. Cl. D34—5 VV

Fig. 1

Fig. 2

Fig. 3

Fig. 4

FIG. 1 is a front elevational view of a polo goal embodying my design,

FIG. 2 is a top plan view thereof,

FIG. 3 is a side elevational view thereof, and

FIG. 4 is a sectional view taken on line IV-IV of FIG. 2.

I claim:

The ornamental design for a polo goal, as shown.
